Attorney

UNITED STATES PATENT OFFICE.

MILTON CURTIS, OF BECKLEY, WEST VIRGINIA.

SHADE ROLLER.

Application filed July 26, 1927. Serial No. 208,494.

The invention relates to shade rollers of the nonspring type, and of the character wherein one end of the roller is provided with a drum around which a cord may be placed and used for rotating the roller, and has for its object to provide a device of this character comprising an elongated body cylindrically shaped and which body is formed in sections semi-circular in vertical transverse cross section and between which sections the upper end of the shade is received and securely clamped by means of securing members extending through the roller body, thereby preventing tearing and obviating the use of tacks and allowing the shade to be easily and quickly applied.

A further object is to provide headed members in the ends of the body between the sections for forming pintles and to provide the ends of the shade with a drum and a sleeve for holding the shade roller ends together, and the pintles in position.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a perspective view of the shade roller.

Figure 2 is a vertical longitudinal sectional view through the roller.

Figure 3 is a transverse sectional view through one end of the shade roller and the drum.

Referring to the drawing the numeral 1 designates the cylindrical elongated body of the roller, and which body is formed from elongated sections 1^a and 1^b. The body sections 1^a and 1^b are semicircular in vertical transverse cross section and when brought together in the position shown in the drawing, form a cylindrical roller. Heretofore it has been the practice to secure the upper end of the shade 2 to the roller by means of tacks, however it has been found that incident to constant use in rolling and unrolling a shade, the shade where simply tacked easily tears from the roller, and to obviate this difficulty the upper end 3 of the shade 2 is placed between the roller sections 1^a and 1^b and

is securely held and clamped therebetween by means of screws 4 which extend transversely through the roller sections 1^a and 1^b, therefore it will be seen that a large gripping surface is provided on the shade and danger of tearing of the shade is obviated. After the shade has been securely clamped between the roller sections, the cord receiving drum 5 and the sleeve 6 are forced over the ends of the roller sections, thereby slightly forcing said roller section ends together for positively gripping and frictionally holding the drum 5 and the sleeve in place. The drum 5 is preferably additionally held by means of a headed screw 7, and to the head of which the cord for wrapping around the drum may be attached in any suitable manner.

The ends of the roller 1 are provided with axially disposed pintles 8 formed from headed members, the heads 9 of which are disposed in registering recesses 10 in the inner adjacent faces of the roller sections 1^a and 1^b, therefore it will be seen that the pintles will be positively held at all times and special holding means other than the heads and recesses is obviated, thereby additionally reducing the cost of manufacture of the roller.

From the above it will be seen that a shade roller is provided, which is simple in construction, the parts reduced to a minimum, and one which may be cheaply manufactured and sold. It will also be seen that a shade roller is provided which is particularly adapted for use in connection with shades carried by rollers, which rollers are rotated by means of a cord anchored to and wound around a drum on the roller.

The invention having been set forth what is claimed as new and useful is:—

A shade roller comprising an elongated cylindrical body, said body being formed from elongated sections semicircular in vertical transverse cross section and adapted to receive therebetween a shade end, securing means extending transversely through said roller sections, pintles extending axially from the ends of the roller, the inner ends of said pintles being provided with heads disposed in registering recesses in the inner faces of the roller sections spaced from their ends.

In testimony whereof I hereunto affix my signature.

MILTON CURTIS.
